UNITED STATES PATENT OFFICE.

JAMES F. ROWLEY, OF CHICAGO, ILLINOIS.

SUSPENDER FOR ARTIFICIAL ARMS.

1,075,861.

Specification of Letters Patent.

Patented Oct. 14, 1913.

Application filed June 28, 1912. Serial No. 706,392.

To all whom it may concern:

Be it known that I, JAMES F. ROWLEY, a citizen of the United States of America, and a resident of Chicago, county of Cook, State of Illinois, have invented certain new and useful Improvements in Suspenders for Artificial Arms, of which the following is a specification.

The main objects of this invention are to provide improved mechanism for operating artificial arms in such manner that the movements of the hand may be controlled so as to simulate more closely, than has heretofore been possible, the movements of the human arm and hand; to provide mechanism of this kind in the form of a suspender which may be readily attached to the wearer's body and adapted to control certain different movements of the hand by movements of the wearer's body which are of such small extent as to be scarcely noticeable to the observer; and to provide mechanism of this kind whereby the finger and wrist movements of the hand may be individually or simultaneously controlled.

A specific embodiment of this invention is illustrated in the accompanying drawings, in which:

Figure 1 is a rear view showing the manner in which the suspender is attached to the wearer's body. Fig. 2 is a front elevation. Fig. 3 is a detail showing the arrangement of the cords or straps which flex the wrist and straighten the fingers of the hand. Fig. 4 is a top view, partly broken away, of an artificial hand and the finger operating mechanism thereof.

The specific device shown in the drawings is designed for an arm intended for use after amputation below the elbow, and comprises a forearm section 1 and an upper arm section 2 which are hinged together so as to provide suitable elbow movement. The upper arm section 2 is connected by suitable straps 3 to a shoulder pad or cap 4, which in turn is connected by straps 5 and 6 extending respectively across the front and back of the wearer's chest to a cap on the other shoulder of the wearer. This cap is shown of skeleton structure, and comprises a looped strap 7 and a strap 8 which may be a continuation of the strap 5, being fastened at both the front and back to the loop 7. The strap 6 is also secured to said loop. The suspender also includes a belt or waist strap 9, and thigh or leg bands 10.

A pair of suitable cords or straps 11 and 12 have their lower ends respectively attached to the sides of the leg bands 10, and are then conducted around fair leader pulleys 13 on the belt 9. The strap 12 passes directly over the shoulder pad 4 on the same side of the body, but the strap 11 passes over a fair leader pulley 14 mounted at the back of the strap 7 on the other shoulder, and then extends across the back over the shoulder pad 4 where it crosses the strap 12. In order to prevent displacement of the straps 11 and 12, where they pass over the shoulder pad 4, they are guided in grooves in the shoulder pad 4, which grooves are covered by strips of leather forming with the pad 4 tunnel-like channels for the cords 11 and 12 to slide in. The cord 12 is guided on the arm members 1 and 2, in suitable manner, either inside or outside of the outer covering thereof, and terminates in a yoke 15 from which extend the cords 16 for operating the fingers.

The specific finger operating mechanism is not illustrated in the drawings, and may be of any suitable form; as for example, one in which the fingers and thumb are normally urged to closed position by suitable springs, and are straightened to open the hand by a pull on the cords 16. If the hand operating mechanism is of the type above described, a pull upon the cord 12 will open the hand and allow it to release whatever may have been held in its grasp.

In the form shown the hand member 17 of the arm is pivoted at 18 to the forearm member 1, to form a wrist joint, and the cord 11 passes down through the forearm section 1, and then over a fair leader roller or guide 19, and its end is attached at 20 to the hand member at a distance from the pivotal center thereof, so that a pull upon the member 11 will cause the wrist to bend in the direction toward which the palm of the hand faces.

The operation of the device shown is as follows: In cases where the amputation has been below the elbow, the artificial arm would be made in somewhat the form in which it is illustrated in the drawings, and the elbow movement would be controlled by the movement of the stump of the wearer's forearm. This normal elbow movement, together with the control of the wrist joint by means of the cord 11, enables the wearer to bring his hand to any desired position.

It will be seen from Fig. 3 that tension on the cord 11 causes the hand to swing toward the palm side, whereas tension on the cord 12 will swing the hand in the reverse direction, if permitted to do so by a release of the tension on the cord 11. If the fingers of the hand are normally urged to a position for engaging the thumb, so as to grasp an interposed article, as hereinbefore described, then tension on the cord 12, if resisted by tension on the cord 11, will cause the hand to open, as illustrated in Fig. 3. Now, referring to Fig. 1 it will be seen that, by reason of the fact that the cord 11 extends from the hip to the shoulder on the same side of the body, an elevation of the wearer's shoulder, so as to elongate the distance between said shoulder and hip, will cause a pull to be exerted on the cord 11. A similar movement of the other shoulder will, for like reason, exert a pull on the cord 12. In this manner the wearer of an artificial right arm may, by raising the left shoulder, cause the hand to swing on the wrist joint, and, by lifting the right shoulder, cause the finger mechanism to open the hand. When the right shoulder is lowered, the hand will close and grip any article which may be interposed between its thumb and fingers. These movements, together with the normal movements of the wearer's upper arm and the stump of the lower arm, enable him to bring the artificial hand to any desired position, and open and close the hand at will in any position.

Although but one specific embodiment of this invention has been herein shown and described, it will be understood that numerous details of the construction shown may be altered or omitted without departing from the spirit of this invention as defined by the following claims.

I claim:

1. A suspender for artificial arms, comprising means for operating the arm and having a part adapted to be attached to the wearer below the waist line, and extending to the arm whereby the latter may be operated by a movement of the wearer's body.
2. An artificial arm suspender, comprising means for operating the arm and having two parts operatively connected to the shoulders of the wearer and attached to the wearer's body below the waist line at opposite sides thereof, and respectively connected to different members of the arm whereby different movements of the trunk of the wearer's

body will individually operate said members.

3. The combination of an artificial arm, adapted to be flexed at the wrist and at the finger knuckles, and operating means comprising parts arranged and connected for controlling the wrist and finger movements respectively, and adapted to be attached to the wearer's body below the waist line for producing the respective wrist and finger movements through different movements of the wearer's body.

4. Operating means for artificial arms, comprising two straps respectively attached to the wearer's body below the waist line, said straps running to different shoulders, and then to different members of the arm mechanism whereby the operation of said members may be individually controlled through movements of the respective shoulders.

5. An artificial arm suspender, comprising straps respectively arranged to control the wrist and finger movements, said straps extending along the arm, over the shoulder, and down the back of the wearer and being adapted to be attached at points below the waist line, one of said straps being also guided by means connected to the opposite shoulder whereby certain movements of the respective shoulders will operate the wrist and fingers.

6. An artificial arm suspender, comprising shoulder caps adapted to be respectively mounted on the wearer's shoulders, a belt passing around the wearer's waist, leg bands, a pair of straps extending from the respective leg bands to different shoulders at the back of the wearer, then over one of the wearer's shoulders and being separately connected for the individual operation of different arm members, and guiding means connected to said belt for directing the strain on the back parts of said straps.

7. A suspender for artificial arms, comprising a pair of flexible tension members operatively connectible to the artificial arm, and attachable substantially to the hips and shoulders of the wearer for control of said arm by relative movements of the hips and shoulders.

Signed at Chicago this 26th day of June 1912.

JAMES F. ROWLEY.
